UNITED STATES PATENT OFFICE.

LEONARD CHARLES HARVEY, OF COUNTY OF SURREY, ENGLAND.

FURNACE.

1,416,406.

Specification of Letters Patent. Patented May 16, 1922.

Application filed August 23, 1918. Serial No. 251,086.

To all whom it may concern:

Be it known that I, LEONARD CHARLES HARVEY, a subject of the King of Great Britain, residing in the county of Surrey, England, have invented certain new and useful Improvements in a Furnace, of which the following is a specification.

This invention relates to a furnace adapted for the melting and pouring of metals, 10 such as brass.

An object of the invention is to provide an improved furnace in which the melting of metal may be carried on without the use of crucibles, and in which oxidization of the 15 metal is much reduced.

A further object is to provide means whereby the metal may be thoroughly mixed and maintained mixed during the melting and pouring operations.

20 A further object is to provide, in combination with the above, means whereby quantities of the molten metal may be readily poured off from a point below the level of the molten metal, and also from a point where 25 the agitation or mixing of the metal is most pronounced and efficient.

30 A more detailed object is to provide a furnace having a hearth or metal-bath lining of pan-like shape therein, to provide pivotal supports for the furnace so that the furnace may be oscillated to a greater or less extent to cause the contents of the hearth to surge back and forth, to so shape the bottom wall of the hearth as to cause considerable agitation throughout the body of the 35 molten metal, and to provide suitable pouring spouts so that the metal may be poured from the hearth at will.

40 Other objects and aims of the invention, more or less specific than those referred to above, will be in part obvious and in part pointed out in the course of the following description of the elements, combinations, arrangements of parts and applications of 45 principles, constituting the invention, and the scope of protection contemplated will be indicated in the appended claims.

50 In the accompanying drawings which are to be taken as a part of this specification, and in which I have shown merely a preferred form of embodiment of the invention:

Fig. 1 is a perspective view of a furnace constructed in accordance with this invention.

Fig. 2 is a transverse sectional view through the furnace shown in Fig. 1.

55

Fig. 3 is a sectional view taken substantially upon the plane of line III of Fig. 2.

60

Fig. 4 is a view similar to that shown in Fig. 3, but being taken substantially upon the plane of line IV of Fig. 2.

65

Referring to the drawings for describing in detail the structure which is illustrated therein the reference character 0 indicates the furnace casing. This is preferably formed of metal and is made in upper and 65 lower sections 1 and 2 so that the upper section may be disconnected and removed whenever it is desired to gain access into the interior of the furnace for the making of repairs or the like.

70

Suitable trunnions 3 project from the opposite ends of the lower section 2, and these are supported in bearing brackets 4 so that the furnace may be readily rocked back and forth.

75

The rocking motion may be imparted to the furnace by hand, or otherwise as may be found most desirable under varying circumstances.

80

Both the upper and lower sections of the furnace are provided with suitable linings L of refractory material such as brick or the like, and one or more funnel shaped openings G are provided through the walls of the upper section for the introduction or 85 application of suitable burners, the flames from the burners being directed into the interior of the furnace in the usual way so that the shape of the openings G serve to spread the flames.

90

A flue E is preferably provided extending upwardly through the upper section for the emission of products of combustion and other objectionable gases. A hanging chimney piece or the like, as 5, may connect with 95 the flue E as clearly illustrated in Fig. 2. A damper F is provided for altering the size of the flue passageway at will.

An inspection door 6 may be provided also through the upper section for inspecting the 100 melting process within the furnace at will.

The hearth, or metal-bath lining M, is formed within the lower section. It is made up of a composite refractory material and is specially shaped substantially as indicated 105 in the drawings. The bottom wall, as 7, ex-

tends substantially flat between the opposite end walls 8 throughout the central portion of the hearth. Near its front edge, however, the level of the bottom wall is raised some what, as at 9, and the surface 10 of the main portion of the bottom wall is connected with the surface portion 9 by a surface portion 11 which is arranged at a steep angle, or incline, the junction between the surfaces 10 and 11 being formed by a smooth concavedly curved surface portion 12, and the junction between the surfaces 9 and 11 being formed by a smooth convexly curved surface portion 13. All of the surfaces 9, 10, 11, 12, and 13 extend continuous between the end wall members 8.

The purpose of shaping the surfaces as just described is to direct the molten metal in an upwardly curved or swirling direction as the furnace is tilted to cause the metal to flow toward the surface 11. As the mass of metal flows against the surface 11 it is directed upwardly, and co-acting with the mass of metal above the surface 9, is caused to roll back upon itself to a greater or less extent according to the violence of movement of the furnace. A certain suction effect is also felt by the metal above the surface 9 so that this metal is constantly agitated and interchanged with the main body.

The surfaces just described may, therefore, be conveniently referred to as the agitating surfaces for the metal.

A pouring spout C is provided for use in pouring small quantities of the molten metal. It will be noted that the spout C is tubular, that it is arranged on an incline, and that its inner end terminates in proximity to the surface 11 at a point below the upper level of the molten metal. By this arrangement any metal poured through the spout C is free of the impurities which are present at the surface of the metal, and is taken directly from that locality where the mixing effect of the agitating surfaces is at its maximum efficiency.

At the rear of the furnace the bottom wall of the hearth inclines gradually upwardly, as at 14, and terminates in a pouring spout D which may be used when it is desired to pour off the entire contents of the hearth, that is, both the molten metal and the slag, or other material which may be present at the surface of the metal. A removable closure member 15 is provided for normally maintaining the spout D closed.

It has been found that the gradual incline of the surface 14 cooperates materially in producing efficient mixing operation of the agitating surfaces. As the furnace is rocked the metal flows, without great disturbance, back and forth along the surface 14 and is thus able to engage the agitating surfaces without the presence of any countering currents which would decrease the

efficient action of the agitating surfaces. A removable closure member 16 is preferably employed for closing the spout C when not in use.

A charge tube A is provided through which the metal may be fed into the furnace. This tube may be made of plumbago or other suitable material. It is arranged in a vertical position and is open at both ends. The lower end rests upon a block K which supports it above the level of the surfaces 10 and 14 of the hearth, and below the level of the molten metal. The block is narrow, as clearly seen in Fig. 3, so as to leave ample openings 17 from the tube at opposite sides of the block. The upper end engages a cover piece H which fits into an opening 18 formed in the upper wall of the furnace, the tube being connected with said cover so as to be readily removable therewith, whenever desired. Suitable lifting eyes 19 may be provided upon the cover by which to remove the same at will.

A hopper B, of metal or other suitable material, is also carried by the cover H in register with the charging tube A and extends above the upper surface of the furnace to conveniently receive the metal to be melted. A cap, or closure J, is carried by the hopper B for closing the same during the melting process.

Vent holes I are provided through the walls of the tube A at a point near its upper end, and a further hole 20 is provided through the cover J so that a certain amount of hot gases may be discharged therethrough to thereby exclude the admission of cold air into the tube.

The position of the lower end of the tube below the level of the molten metal forms a seal which, with the seal afforded by the presence of hot gases in the upper portion of the tube, to a great extent prevents the presence of oxygen about the metal within the tube. The metal within the tube is subjected to great heat, not only from all portions of the tube and from the molten metal beneath it, but also from the flames which may pass into the tube through the openings I. The metal which is within the tube, and therefore, sealed against the oxidizing effects of the outside air, will melt and flow downwardly as in a crucible. It will flow through the open lower end of the tube and spread over the floor of the hearth.

In operation the metal to be melted is introduced into the tube A through the hopper B and, when subject to the heat from the burners in the openings G, melts and flows over the floor of the hearth. The metal may be continually fed into the tube and may be as continually poured off from the hearth. All of the pouring for castings or like purposes, will be from the spout C. During the melting operation, or at any

other desired time, the furnace may be kept 5 rocking upon its supports so that the liquid metal will flow back and forth over the agitating surfaces of the hearth. The metal will thus be kept thoroughly mixed, the metal being given a circular, or swirling motion upwardly and over upon itself with each movement against the surface 11. The closure 16 of the pouring spout C may be 10 removed at any time and the furnace held suitably tilted so that the metal will flow directly from the agitating surfaces through said spout.

Since both the pour-out spout C and the 15 lower end of the tube A stand normally beneath the level of the molten metal, it is apparent that any slag or like material upon the surface of the metal will be held above the level of these parts. That is, the metal 20 flowing downwardly from the tube A would enter the body of molten metal at a point beneath such slag and would remain beneath the slag until poured off through the spout C. By thus disposing the inlet and outlet 25 openings the slag is left to serve as a protective cover over the melted metal at all times and is effective in excluding oxidizing agents from the metal.

After the day's work is done the remaining 30 contents of the hearth may be poured off through the spout D. The charging tube may be lifted out for cleaning, repairs, or otherwise, and while removed access is readily afforded through the top wall of the furnace for scraping out or otherwise cleaning 35 the interior of the furnace.

As many changes could be made in this construction without departing from the scope of the invention as defined in the following 40 claims, it is intended that all matter contained in the above description, or shown in the accompanying drawings, shall be interpreted as illustrative only and not in a limiting sense.

Having thus described my invention, 45 what I claim as new and desire to secure by Letters Patent is:—

1. A furnace, means whereby the furnace may be bodily moved to cause a back and forth motion of liquid within the furnace 50 having a relatively flat surface portion, a floor within the furnace over which the liquid is adapted to flow, and said floor being shaped to provide an abruptly inclined surface portion against which the liquid is 55 adapted to flow to thereby agitate and mix the liquid as the body of liquid moves in one direction, and said floor being shaped to provide a further relatively flat surface portion 60 extending from the level of the upper edge of said inclined surface portion adapted to assist in the agitation of the liquid.

2. A furnace, means whereby the furnace may be bodily moved to cause a back and 65 forth motion of liquid within the furnace, a

floor within the furnace over which the liquid is adapted to flow, said floor having agitating surfaces at one side thereof against which the liquid is adapted to engage when the liquid flows in one direction, a pour out 70 spout disposed adjacent said agitating surfaces, said floor being provided with a non-agitating surface at its opposite side for the purpose described, and a pour out spout disposed adjacent said non-agitating surface. 75

3. A furnace, means whereby the furnace may be bodily moved to cause a back and forth motion of liquid within the furnace, a floor within the furnace over which the liquid is adapted to flow, said floor having agitating 80 surfaces at one side thereof against which the liquid is adapted to engage when the liquid flows in one direction, and a pour out spout disposed adjacent to said agitating surfaces. 85

4. A furnace, means whereby the furnace may be bodily moved to cause a back and forth motion of liquid within the furnace, a floor within the furnace over which the liquid is adapted to flow, said floor having agitating 90 surfaces at one side thereof against which the liquid is adapted to engage when the liquid flows in one direction, and a pour out tube having its inner end terminating adjacent to said agitating surfaces. 95

5. A furnace, means whereby the furnace may be bodily moved to cause a back and forth motion of liquid within the furnace, a floor within the furnace over which the liquid is adapted to flow, said floor having agitating 100 surfaces at one side thereof against which the liquid is adapted to engage when the liquid flows in one direction, and a pour out tube arranged at an incline and being disposed so that its inner end terminates beneath the level of the liquid and adjacent to said agitating surfaces. 105

6. A furnace, means whereby the furnace may be bodily moved to cause a back and forth motion of liquid within the furnace, 110 a floor within the furnace over which the liquid is adapted to flow, said floor having agitating surfaces at one side thereof against which the liquid is adapted to engage when the liquid flows in one direction, a pour out 115 spout adjacent to said agitating surfaces, and a second pour out spout removed from said agitating surfaces.

7. A furnace comprising a hearth adapted to contain a quantity of molten metal, an open ended charging tube extending into the furnace, having its lower open end terminating within the hearth above the floor thereof and below the level of the molten metal, said charging tube being adapted to 120 contain the metal to be melted, means whereby melting heat may be applied into the interior of the furnace around said charging tube, and said charging tube having 125 openings through the upper portion thereof 130

- through which a portion of said heat may enter the tube into and above the metal to be melted to thereby constitute a seal against oxygen above the metal to be melted.
5. 8. A furnace comprising a hearth adapted to contain a quantity of molten metal, an open ended charging tube extending into the furnace adapted to contain the metal to be melted and to discharge molten metal into the hearth, means whereby melting heat may be applied into the interior of the furnace, and means to provide a seal against admission of oxygen to the metal within the tube.
10. 9. A furnace having a floor therein adapted to contain a liquid, agitating means for said liquid, and a pour out spout disposed adjacent to said agitating means.
15. 10. A furnace having a floor therein adapted to contain a liquid, means for moving the floor adapted to cause the liquid to flow across the floor, agitating means for the liquid comprised in the floor, and a pour out spout disposed adjacent to said agitating means.
20. 11. A furnace having a floor therein adapted to contain a liquid, means for moving the floor adapted to cause the liquid to flow across the floor, agitating means comprised in the floor at one side thereof operable for agitating the liquid as the liquid flows toward said side, said floor at the opposite side thereof being shaped to provide a gradual upward incline along which the liquid may flow and return without great disturbance, and a charging tube extending into the furnace between said portions of the floor.
25. 12. A furnace comprising a hearth adapted to contain a quantity of molten metal, an open ended charging tube extending into the furnace adapted to contain the metal to be melted and to discharge the molten metal into the hearth, means whereby the furnace is movably supported whereby to cause the molten metal to flow across the floor of the hearth, and agitating means comprised in the hearth spaced from said tube adapted to agitate the metal flowing thereto.
30. 13. A furnace having a floor therein adapted to contain a liquid, means for moving the floor adapted to cause the liquid to flow across the floor, a charging tube extending upwardly above said floor and movable therewith, and agitating means for the liquid comprised in said floor.
35. 14. A furnace having a floor therein adapted to contain a liquid, means for moving the floor adapted to cause the liquid to flow across the floor, and a charging tube extending upwardly above said floor and movable therewith.
40. 15. A furnace having a floor therein adapted to contain a liquid, and also having an upper wall spaced above said floor, means whereby the furnace may be bodily moved to cause a back and forth motion of liquid across said floor, and a charging tube carried by and movable with the furnace extending upwardly from adjacent said floor 70 and through said top wall.
45. 16. A furnace having a floor therein adapted to contain a liquid, means for moving the floor adapted to cause the liquid to flow across the floor, agitating means comprised in the floor at one side thereof operable for agitating the liquid as the liquid flows toward said side, said floor at the opposite side thereof being shaped to provide a gradual upward incline along which 80 the liquid may flow and return without great disturbance, and a charging tube extending into the furnace terminating spaced above the upper surface of said floor 75 between said mentioned portions of the floor.
50. 17. A furnace having a floor therein adapted to contain a liquid, means for moving the floor adapted to cause the liquid to flow across the floor, agitating means comprised in the floor at one side thereof operable for agitating the liquid as the liquid flows toward said side, said floor at the opposite side thereof being shaped to provide a gradual upward incline along which 90 the liquid may flow and return without great disturbance, a charging tube extending into the furnace between said mentioned portions of the floor, and means carried by said floor serving to support said charging tube spaced above said floor.
55. 18. A furnace having a floor therein adapted to contain a liquid and also having a portion providing an enclosure above said floor, a charging tube extending upwardly from adjacent said floor and through said enclosure forming portion, and said charging tube having an opening formed through the upper portion thereof within said enclosure for the purpose described.
60. 19. A furnace having a floor therein adapted to contain a liquid, means for moving the floor adapted to cause the liquid to flow across the floor, and a charging tube extending upwardly above the floor being movable therewith and having its lower end 105 open and terminating below the level of the liquid upon said floor.
65. 20. A furnace having a floor therein adapted to contain a liquid, means for moving the floor adapted to cause the liquid to flow across the floor, and a charging tube extending upwardly above the floor being movable therewith and having its lower end open and terminating below the level of the liquid upon said floor, together with a pour-out spout adjacent said floor also having its inner end terminating beneath the level of said liquid.
70. 21. A furnace designed to be rocked, oscillated or otherwise moved in such man- 130

ner as to mix the molten metal therein, provided with means whereby material floating upon the surface of the molten metal can be maintained as a protective 5 cover for the metal and whereby the metal to be melted can be introduced beneath such protective cover, substantially as described.

In testimony whereof I affix my signature in the presence of two witnesses.

LEONARD CHARLES HARVEY.
